(No Model.)

D. S. RANDOLPH.
Steam Brake for Locomotives.

No. 241,511.

Patented May 17, 1881.

ATTEST:

Robt Burns
George Bullock

INVENTOR:

David S. Randolph.

UNITED STATES PATENT OFFICE.

DAVID S. RANDOLPH, OF ST. LOUIS, MISSOURI.

STEAM-BRAKE FOR LOCOMOTIVES.

SPECIFICATION forming part of Letters Patent No. 241,511, dated May 17, 1881.

Application filed August 26, 1880. (No model.)

To all whom it may concern:

Be it known that I, DAVID S. RANDOLPH, a citizen of the United States, and a resident of St. Louis, in the State of Missouri, have invented a certain new and useful Improvement in Steam-Brakes for Locomotives, &c.; and I do hereby declare that the following is a full, clear, and exact description of the same, reference being had to the accompanying drawings, forming part of this specification.

This invention relates to certain improvements in that class of locomotive-brakes in which a steam-cylinder is arranged between the driving-wheels and connected and operating the brake-shoes of both wheels; and the present improvement consists, first, in the provision of a fixed vertical cylinder supported on a bracket-plate secured to the frame of the locomotive, the piston-rod of which cylinder has connection, by suitable links or their equivalent, with a pair of bell-crank levers pivoted in the brake-heads and to the ends of an adjustable stay or distance rod, so that any upward movement of the piston-rod will tend to apply the brake-heads, the brake-heads being supported by links or hangers dependent from a bracket secured to the locomotive-frame; secondly, in a construction and arrangement of parts, as hereinafter more fully set forth, whereby the brake-shoes proper are attached to the brake-heads without the use of rivets or bolts; thirdly, in certain details of construction, as will hereinafter more fully appear.

In the drawings, in which similar letters of reference indicate like parts, Figure 1 is a side elevation illustrating my invention. Fig. 2 is a transverse section. Fig. 3 is a detail sectional plan of piston-rod and connections to draw-links. Fig. 4 is a perspective view of the hanger-bracket for hanger-links of brake-heads.

A A' are portions of the locomotive-frame, to which the bracket-plate B is secured by the channel-plate C extending between the frame A A', and rigidly bolted thereto and to the plate B, as shown in Fig. 2. The upper end of the frame or plate B is formed with a horizontal bracket, b, upon which is arranged the vertical cylinder D, having a stuffing-box, D', at its lower end, through which passes the piston-rod d. At its lower end the piston-rod is

formed into an eye, d', at each side of which is attached eye-plates e to form a cross-head, and between which the pull rods or bars E are pivoted, as clearly indicated in Figs. 1, 2, and 55 3. The pull-rods E are pivoted at their lower ends to the long arms f f' of bell-crank levers F F, that are pivoted at their elbows f' f' in the brake-heads G and at the ends of their short arms in the distance or stay rod H. 60

With this construction it will be readily seen that any upward movement of the piston will apply the brake-heads to the wheels, and that when the steam is allowed to escape from the operating-cylinder D the brake-heads will 65 swing away out of contact with the wheels by their own weight.

The brake-heads G G are supported by hangers G² G², pivoted at g in a recess in the brake-heads, and at g' to the hanger-bracket I, which 70 is formed with a flat portion, i, by which it is secured to the plate B, outwardly-bent portion i', and pivot-lugs i² for the hangers G², as clearly indicated in Fig. 4, the purpose being to bring the pivot-points g' i² out to or near the center 75 line of the brake-heads, and thus obviate the necessity of bending the hangers G², or require but a very slight bend in the same.

The distance or stay rod H is made adjustable in the following manner, so as to allow of 80 the adjustment of the brake-blocks with relation to the wheels: The rod is divided into two portions, h h', one of which has a right-hand and the other a left-hand screw-thread. On these two portions the right-and-left-hand- 85 screw-threaded sleeve H' screws to adjust the length of the rod.

h² are lock-nuts to hold the parts in the position to which they are set.

The rod H is provided at each end with ears 90 h³ for the reception of set-screws h⁴, that bear against the lower end of the brake-head, and by means of which said brake-heads are adjusted in proper relative position to the locomotive drive-wheels and their upper ends kept 95 from rubbing on said wheels when not in use.

J is a bracket-plate, similar in construction to the hanger-bracket I, and having ears j, which form guides for the brake-head and prevent any outward movement of the same. 100

The brake-heads G G are formed of the ordinary cast-iron heads or blocks, G, and wrought

shoes G', which are T-shaped in cross-section and fit into recesses in the heads, the top portion, g², of said shoes being reduced and bent over the upper end of the web g³, as clearly indicated in Figs. 1 and 5 of the drawings, the purpose being to support the shoe and hold it in proper position without the use of bolts or rivets ordinarily used for such purpose.

I claim—

- 10 1. The combination, in a steam-brake for locomotives, &c., of the vertical fixed cylinder D, pull-rod E, connected direct to bell-crank levers F, distance-rod H, and brake-blocks G, all arranged substantially as and for the purpose set forth.
- 15 2. The combination, in a brake for locomotives, &c., of the distance-rod H, consisting of parts h h', provided with ears h³ for the reception of set-screws h⁴, adjusting-sleeve H', and lock-nuts h², as described, and for the purpose set forth.
- 20 3. The combination, in a brake for locomotives, &c., of the cylinder D, with piston-rod d, having eye d' at its lower end, eye-plates e, and pull-rods E, all arranged as described, and for the purpose set forth.
- 25 4. The combination, in a brake for locomotives, &c., of the bracket-plate I, constructed and arranged as described, and brake-head 30 hangers G², as and for the purpose set forth.
- 30 5. The combination, in a brake for locomotives, &c., of the brake-heads G and stay-rod H, provided with ears h³ and set-screws h⁴, all arranged as and for the purpose set forth.
- 35 6. The combination, in a brake-head for locomotives, &c., of the head G and shoe G',

when said shoe is secured to the head by having its top portion, g², bent over the upper end of the web g³ of the head G, substantially as and for the purpose set forth.

7. In a steam or similar brake for locomotives, &c., the combination, with the brake-heads, of a distance-rod, elbow or bell-crank levers pivoted on the distance-rod and on the brake-heads, a vertical cylinder fixed to the frame above and on a line passing between the brake-heads, and intermediate pull-rods or links for connecting the piston-rod of the cylinder directly to the bell-crank levers, all constructed and adapted to operate substantially as and for the purpose specified.

8. In a steam or similar brake for locomotives, &c., the combination, with the brake-heads, of a distance-rod adapted to bear against the lower part of the brake-heads, elbow or bell crank levers pivoted to the distance-rod and brake-heads, a vertical fixed cylinder, and links or pull-rods for connecting the bell-crank levers with the piston-rod of the cylinder, substantially as and for the purpose specified.

9. In a locomotive or similar brake, the combination, with the brake-head, of a hanger pivoted thereto and to a hanger-bracket, a hanger bracket for supporting the brake-head, and a guide-bracket for preventing the outward movement of the brake-head, substantially as and for the purpose specified.

DAVID S. RANDOLPH.
